[57] CLAIM

The ornamental design for a water pipe, as shown and described.

DESCRIPTION

FIG. 1 is a perspective view of my ornamental design of a water pipe;

FIG. 2 is a fragmentary front elevational view thereof;

FIG. 3 is a fragmentary side elevational view with the opposite side being a mirror image thereof;

FIG. 4 is a fragmentary rear elevational view thereof;

FIG. 5 is a top elevational view thereof; and,

FIG. 6 is a bottom elevational view thereof.

The fragmentary views in FIGS. 2, 3 and 4 are shown for convenience of illustration.
